(57) **CLAIM**

The ornamental design for a stringed instrument body, as shown and described.

DESCRIPTION

FIG. 1 is a perspective view of a stringed instrument body showing my new design;

FIG. 2 is a front elevation view thereof;

FIG. 3 is a rear elevation view thereof;

FIG. 4 is a left side elevation view thereof;

FIG. 5 is a right side elevation view thereof, and,

FIG. 6 is a bottom plan view thereof.

The broken lines shown in FIGS. 1-6 are for illustrative purposes only and form no part of the claimed design.
